UNITED STATES PATENT OFFICE.

BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,100,455.

Specification of Letters Patent. Patented June 16, 1914.

Original application filed June 30, 1903, Serial No. 163,704. Divided and this application filed October 8, 1912. Serial No. 724,540.

To all whom it may concern:

Be it known that I, BURNHAM C. STICKNEY, a citizen of the United States, residing in Elizabeth, in the county of Union and 5 State of New Jersey, have invented certain new and useful Improvements in Type-Writing Machines, of which the following is a specification.

This invention relates to typewriting machines, and particularly to so-called "visible" writing machines, in which the line of writing is always in view, and more especially to those of the "front strike" class.

My invention consists in certain combinations of devices, features of constructions, and arrangements of parts, which will be hereinafter described and particularly pointed out in the concluding claims, and is a division of my application No. 163,704, 20 filed June 30, 1903.

The principal feature covered herein is the connection between the key-operated universal bar on the main framework of the machine, and the carriage, which shifts up 25 and down, said connection being a train of escapement mechanism extending from the universal bar to the carriage, and including members which are connected at a point which coincides with the axis about which 30 the carriage shifts up and down, so that the effect of the escapement train is the same at both positions to which the carriage is shifted.

In the drawings forming part of this 35 specification, Figure 1 is a longitudinal sectional elevation of a front strike writing machine embodying my improvements; one type action being shown in printing position. Fig. 2 is a front view of the machine, 40 showing the carriage tilted up to expose the underside thereof, and give access to the carriage-spring tension adjusting devices.

The framework of the machine comprises 45 side walls and rear walls forming a base 1, and a depressed top plate 3. Forwardly extending type bars 4 are pivoted at their rear ends upon a curved fulcrum-rod 5 mounted in a segment 6, and strike rearwardly against a platen 7. The segment is radially slotted at 8 to receive the type-bar hubs. 50 Each type-bar is provided with a lower-case type 9 and an upper-case type 10, the

latter being uppermost when the type-bar is in printing position, although this relation may be reversed within the scope of certain 55 features of my improvements, and the type-bars may be otherwise mounted. The type-bars may be operated by any suitable means, as for instance pull-links 11, extending rearwardly and downwardly from the type-bars, 60 pendent levers 12 connected between their ends at 13 to said links, a horizontal rod 14 whereon said levers are fulcrumed at their upper ends, horizontal links 15 connected at 16 to the lower ends of said levers and 65 extending forwardly, and key-bearing bell-cranks fulcrumed upon a transverse rod 17 and having pendent arms 18 connected at 19 to said links 15, and forwardly-extending arms 20 bearing the keys 21. Returning 70 springs as 22 may be provided for the type actions.

The platen 7 may be mounted by means of an axle 25 upon a carriage 26, which may be of any suitable construction, but preferably 75 comprises upper and lower bars 27 and 28, the former provided in its underside with a longitudinal groove 29, and the latter in its 80 underside with a longitudinal groove 30; these bars being connected at their ends by 85 upright bars 31 and 32 formed integral therewith. An integral plate or bar 33 projects forwardly from said connected bars, and at its ends is formed with upright arms 34 and 35 in which the platen axle 25 is journaled. Embraced by the grooved bars 27 and 28 is a rail 36, set on edge and provided in its top and bottom edges with grooves 37 and 38, which are provided with bearing 90 balls 39, whereon the carriage runs. Said 95 grooved rail 36 forms part of a movable frame, whereby the paper carriage is enabled not only to run in letter-feeding direction, but also to move in a direction transverse thereto. This frame comprises, 100 in addition to said rail (which may be otherwise formed in some cases) rearwardly extending integral arms 65, which are united at their forward ends by said rail, and a bar 66, which unites said arms between their 105 ends and is integral therewith. Said arms are extended rearwardly from said bar 66, forming ears 67 and 68, which are hinged by pintles 69 in bosses 70 and 71 which pro-

ject inwardly from the tops of the side walls of the framework 1. The carriage together with its supporting frame may be swung or tilted up about said hinges, so as 5 to expose the underside of the carriage, as at Fig. 2. Said supporting frame may, however, be otherwise formed and otherwise movably supported within the scope of my improvements.

10 A carriage-feeding mechanism is mounted upon the hinged carriage-supporting frame and coöperating with a rack 106 on the carriage; said feeding mechanism comprising upright detent and feeding dogs 107 and 108, the latter normally in engagement with the rack. The rack is mounted upon the rear ends of hinged arms 109 and 110, the latter being prolonged forwardly of its hinge and provided with a depressible carriage-release key 111. The dogs are mounted upon one end of a rock-shaft 112, journaled in a boss 113 formed upon an arm 114 directed upwardly and forwardly from the shifter-frame bar 66; and said shaft at its 25 other end is provided with an operating arm 115, which at its rear end is pivoted at 116 to a pendent link 117, whereby the arm is operated; said pivot 116 being normally substantially coincident with the axis of the 30 hinge 69 of the carriage-supporting frame, so that the operation of the escapement mechanism is substantially the same whether the frame is in normal position or shifted up to write capital letters. At its lower end 35 said link is pivoted at 118 to the forward end of a rocker-arm 119, which projects forwardly from a horizontal transverse rock-shaft 120. A universal bar 121 is mounted upon the tops of a pair of arms 122 which rise from said rock-shaft; and lies in rear of the levers 12 of the type-actions, so 40 as to be operated thereby, as at Fig. 1; the described universal-bar frame being provided with a returning spring 123.

45 The carriage feeding mechanism of a typewriting machine comprises a universal bar such as 121, and a carriage rack such as 106 and intervening connections. In this instance, the connections comprise arms 122, 50 119, link 117, arm 115, shaft 112, and dogs 107 and 108. In this train of mechanism, one of the working joints, namely 116, is normally about in line with the axis of the hinge 69 upon which the frame 65 swings 55 up. Hence the type keys 21, which are on the stationary main frame of the machine, are enabled to control the operation of the escapement dogs 107 and 108 whether the shift frame 36, 65, 67 is up or down. So 60 long as this result is obtained, it is not material whether the joint 116 or some other joint in the carriage feeding train is coincident with the axis 69. It will be noticed that the path of movement of the pivot 116 65 may intersect the axis of the hinge 69,

whereby the link 117 will have the same effect on the escapement dogs 107 and 108 at all printing positions of the platen.

The carriage may be propelled by a spring-barrel 127, lying horizontally and mounted upon the lower end of a stud 128 depending from the hinged carriage-frame; a strap 129 being attached to the barrel and caught upon a hook 130 upon the carriage bar 28. A ratchet wheel 131 and pallet 132 are provided for adjusting the tension of the spring, the former having a finger-piece 133 and the latter a finger-piece 134, both of which in normal position project downwardly, the ratchet-wheel and pallet being mounted below the spring barrel. When the carriage is tilted up, as at Fig. 2, access is given to the ratchet wheel and pallet, thus facilitating the adjustment of the spring. By mounting the spring barrel and the carriage-feeding mechanism upon the hinged frame, the latter is permitted to swing freely up and down, without liability of deranging the carriage-controlling devices, which always preserve their proper relation to the carriage. Preferably advantage is also taken of the hinging of the carriage-support, to enable the latter to be shifted up and down to enable different types to print. Normally the carriage and platen are in the 95 lowermost position, as in full lines at Fig. 1, thereby enabling the lower-case types 9 to print; while by elevating the carriage and platen, as indicated by the dotted circle 7, the upper case types 10 are enabled to print. The downward movement of the carriage is limited by an adjustable stop 136, threaded forwardly through an arm 137 cast upon the rear wall of the machine framing; arm 78 of the hinged carriage supporting frame being prolonged, as at 138, to bear against said 100 adjustable stop.

A shift-lever 139, bearing a key 140, projects forwardly and upwardly from a transverse horizontal rock-shaft 141, journaled in the side walls of the base; and about midway of its length said shaft is provided with an upright arm 142, from which extends rearwardly a link 143, whose rear end has a sliding bearing at 144 in the upper portion of said cast arm 137. Said link is provided with a lug 145, adapted to catch a nib 146 formed upon a hook-shaped stop 147 pivoted at 148 to the lower portion of said arm 78. By depressing the shift key, 115 the shaft 141 and arm 142 thereon are rocked, pulling forwardly the link 143, and by means of the lug 145 and nib 146 swinging the stop down, until the said nib is arrested by a stop pin 149. Continued movement of the key, rock-shaft, arm and link then swings the frame arm 78 forwardly and the frame and carriage upwardly about the hinge 69, until the parts are arrested, 120 with the platen in the dotted line position, 125

by the contact of the hook-stop 147 with the upper end of said cast arm 137 (which of course may be provided with an adjustable stop, if desired.) After the capital type 5 or types are written, the shift key is returned to normal position by a spring 150, while the hinged frame and carriage return by gravity. A spring 151 lifts the hook-stop 147 until it is again clear of the upper end 10 of said cast arm 137, so that it may not contact therewith to interfere with the upward tilting movement of the carriage to the Fig. 2 position. During such tilting movement, the arm 78 and parts thereon are swung forwardly away from their coöperating parts 15 mounted in the machine base; so that at any time the carriage may be given either a limited movement for writing capitals, or a tilting movement to expose the underside 20 thereof.

Wide variations may be resorted to within the scope of my invention, and portions of my improvements may be used without others.

25 Having thus described my invention, I claim:

1. In a front strike writing machine, the combination with types, of a paper carriage having grooved bars, a rail having 30 grooves in its edge, balls running in the grooves, rearwardly extending hinged arms formed integral with said rail, a bar connecting said arms, said arms, bar and rail forming a frame, carriage-propelling devices 35 mounted upon said hinged frame, escapement members also mounted on said frame, and an escapement rack on the carriage and releasably connecting with said escapement members.

40 2. In a front strike writing machine, the combination of a series of type actions including rearwardly striking type-bars, a paper carriage, a frame whereon said carriage is mounted, said frame being hinged in rear of the platen to the framework of the machine, and a train of carriage-escapement devices including a member mounted upon 45 said frame and having an arm, and also including both a link pivoted to said arm at a point which normally substantially coincides with the hinge of said frame, and a universal-bar operable by the type actions and connected to said link.

55 3. In a front strike writing machine, the combination of a series of rearwardly striking type-bars, a paper carriage, a frame whereon said carriage is mounted, said frame being hinged in rear of the carriage to the frame-work, whereby the frame and carriage 60 may be tilted to expose the underside thereof; a train of carriage-escapement devices at least a portion of which are mounted upon said frame, and a carriage-propelling spring provided with tension-adjusting 65 means and mounted at the lower portion of

said frame, so as to be brought into an accessible position when the frame is tilted.

4. In a front strike writing machine, the combination with rearwardly striking types and means for operating them, of a platen, 70 a carriage, a hinged frame whereon said carriage runs, a carriage-propelling spring upon said frame, escapement members upon said frame, including an escapement-operating arm, a link pivoted to said escapement arm at a point normally substantially coincident with the axis of said carriage frame hinge, and a universal-bar or member connected to said link and operable by the type actions. 75

5. In a front strike writing machine, the combination with rearwardly striking types, of a carriage, a frame whereon said carriage runs, said frame being hinged in rear of the carriage so that it can be tilted up to expose the underside of the carriage, an escapement member on said frame, and a carriage-propelling spring also mounted on said frame in a horizontal position and provided upon its underside with a tension-adjusting ratchet, which is normally inaccessible, but which is brought to accessible position by tilting up said frame. 80

6. In a front strike typewriting machine in which the type strike the front side of the 95 platen, the combination of a laterally-movable carriage, a shift-frame which supports the carriage and is pivoted to the main frame in rear of the carriage to shift the carriage vertically, and a carriage feeding 100 mechanism arranged in part on the shift-frame and in part on the main frame with the operative connection between said parts substantially in the pivotal axis of the shift-frame, substantially as set forth. 105

7. In a typewriting machine, the combination of a laterally-movable carriage, a shift-frame pivoted to the main frame and supporting the carriage, and a carriage-feeding mechanism having one part supported 110 by the main frame and another part supported by the shift-frame, with the working joint between said parts of the feeding mechanism coincident with the pivotal axis of the shift-frame, substantially as set forth. 115

8. In a front strike typewriting machine in which the type strike the front side of the platen, the combination of a laterally-movable carriage, a shift-frame which supports the carriage and is pivoted to the main 120 frame in rear of the carriage to shift the carriage vertically, and a carriage-feeding mechanism arranged in part on the shift-frame and in part on the main frame with the operative connection between said parts 125 in the pivotal axis of the shift-frame, substantially as set forth.

9. In a typewriting machine, the combination of a laterally-movable carriage, a shift-frame pivoted to the main frame and 130

supporting the carriage, and a carriage-feeding mechanism having one part supported by the main frame and another part supported by the shift-frame, with the working joint between said parts of the feeding mechanism on the pivotal axis of the shift-frame, substantially as set forth.

10. The combination of a carriage, a pivoted shift-frame, and key-controlled means for feeding the carriage, said key-controlled means being mounted partly upon said shift-frame and partly upon a portion of the machine with relation to which said shift-frame is shifted, the engagement between the members on the shift-frame and the members not mounted on said frame being in the axis of the pivotal movement of said shift-frame.

11. A typewriting machine having in combination, a main frame, a carriage, a shift frame which supports the carriage and which is hinged or pivoted to the main frame, and a train of carriage-feeding devices, certain members of which are on the carriage shift frame and certain members of which are on the main frame, the point of engagement of the members on the shift frame with the members on the main frame being in the axis of the shift frame hinge.

12. In a typewriting machine in which the types strike the front side of the platen, the combination of a main frame, a carriage, a shift frame which supports the carriage, said shift frame being pivoted to the main frame in rear of the carriage to shift the carriage up and down, and a train of carriage-feeding members extending from the carriage on the shift frame, and including a member on the main frame, the point of engagement of the main-frame member with a member on the shift frame being in the axis of said shift frame.

13. The combination of a carriage, keys, a shift frame for the carriage pivotally mounted, feeding members for said carriage having at least part thereof mounted on said shift frame, and a connection between the keys and said carriage through said feeding members having part of said connection in the pivotal axis of said shift frame.

14. In a typewriting machine, the combination with a traveling carriage, of a shift-frame pivotally mounted, a feeding mechanism for said carriage having at least part of it mounted in said shift-frame, and a connection between the keys and said carriage through said feeding mechanism having part of said connection in the pivotal axis of said shift-frame.

15. In a typewriting machine, the combination with a traveling carriage, of a pivotally mounted shift frame for said carriage, a feeding mechanism for said carriage comprising an escapement rack or set of teeth mounted on said shift frame, and also

comprising means coincident with the pivotal axis of said shift frame for controlling said escapement rack, and also comprising key-operated means on the main frame of the machine.

70

16. In a typewriting machine, the combination with a traveling carriage, of a shift frame pivotally mounted on which said carriage travels, a feeding mechanism comprising an escapement rack or set of teeth mounted on said shift frame, and also comprising a vibrating member by which said escapement rack is controlled, said member mounted for movement in a path which intersects the pivotal axis of said shift frame, and also comprising key-operated means on the main frame of the machine.

75

17. In a typewriting machine, the combination with a traveling carriage, of a pivotally mounted shift frame on which said carriage travels, a feeding mechanism for said carriage comprising a rack bar traveling with said carriage, and also comprising a vibrating member on the frame of the typewriter, and also comprising a connection for controlling said rack by said vibrating member, said connection mounted for movement in a path which intersects the pivotal axis of said shift frame, and also comprising key-operated means on the main frame of the machine.

85

18. In a typewriting machine, the combination with the main frame, of a carriage shift support pivotally connected to the main frame, a laterally movable carriage arranged to vibrate with the pivoted support, and letter-feeding mechanism for said carriage, said letter-feeding mechanism forming a connection between the carriage and the main frame, and including means whereby it remains connected with the main frame at all positions of said carriage shift support.

100

19. In a front strike typewriting machine, the combination of a laterally movable carriage, a shift frame supporting the carriage, and a pivotal connection between the main frame and the shift frame located in rear of the carriage, and a carriage feeding mechanism arranged with the operative connection between the same and the carriage in the pivotal axis of the shift frame, substantially as set forth.

110

20. In a front strike typewriting machine, the combination of a laterally movable carriage, a frame pivoted to the main frame and supporting the carriage, and a carriage feeding mechanism having one part supported by the main frame and another part supported by the pivoted frame, with the working joint between said parts in the pivotal axis of the pivoted frame, substantially as set forth.

115

21. In a front strike typewriting machine in which the type strike the front side of

125

130

the platen; the combination of a laterally-movable carriage, a shift-frame which supports the carriage and is pivoted to the main frame in rear of the carriage to shift the carriage vertically, and a train of carriage-escapement devices arranged in part on the shift-frame and in part on the main-frame to be operated by the type keys, with the operative connection between said parts in the pivotal axis of the shift-frame.

22. In a typewriting machine, the combination of a laterally-movable carriage, a

shift-frame pivoted to the main frame and supporting the carriage, and a train of carriage-escapement devices having one part 15 supported by the main frame and another part supported by the shift-frame, with the working joint between said parts of the escapement in the pivotal axis of the shift-frame.
